UNITED STATES PATENT OFFICE.

FREEMAN R. WILLSON, JR., OF WORTHINGTON, OHIO, ASSIGNOR, BY MESNE ASSIGNMENTS,
TO THE JEFFREY MANUFACTURING COMPANY, A CORPORATION OF OHIO.

STEAM-TIPPLE.

No. 890,321.

Specification of Letters Patent.

Patented June 9, 1908.

Application filed July 13, 1904. Serial No. 216,453.

To all whom it may concern:

Be it known that I, FREEMAN R. WILLSON, Jr., a citizen of the United States, residing at Worthington, in the county of Franklin and 5 State of Ohio, have invented certain new and useful Improvements in Steam-Tipples, of which the following is a specification, reference being had therein to the accompanying drawing.

10 This invention relates to an improved mechanism for unloading cars while they are standing upon the track, it relating more particularly to mechanism of the class by which cars are tilted on transverse axes, 15 that is to say by which each car is lifted at one end in order that its load may be discharged by falling out at the other end.

Among the purposes of the invention is this, to simplify the apparatus by dispensing 20 with many of the parts that have been heretofore essential and so constructing and arranging those that are employed that the apparatus can be constructed at a minimum cost and yet have the power applied with the 25 utmost economy.

Figure 1 is a side view of the mechanism embodying my improvements. Fig. 2 is a plan view. Fig. 3 is a vertical longitudinal section of the lifting engine. Fig. 4 is a 30 view partly in section and partly in elevation of the stop for preventing the cars from moving backward. Fig. 5 is a plan view of the parts of Fig. 4. Fig. 6 is a cross section of a fragment of the cylinder on the line $x-x$. 35 Fig. 3. Fig. 7 is a cross section of a fragment of the cylinder on the line $y-y$. Fig. 3. Fig. 8 is a view of a modification of the draft rod interposed between the car stop and the rock shaft which moves the stop.

40 In the drawings there is illustrated a track system having the principal parts A—A¹. The cars are passed to the unloading apparatus over the track section A, this being somewhat inclined toward the said apparatus, 45 and the section at A¹ is more sharply inclined, in order that the cars after being emptied can pass rapidly on and away from the position occupied when unloading. These track sections are supported in elevated positions upon suitable framework, as indicated at B—B¹, which can be varied to meet the circumstances that are met with.

Heretofore it has been customary in car unloading or tippling mechanisms of this

class to employ at one point or another rising 55 and falling rails or bars, contacting with the car wheels and moving up or down with the cars to cause the unloading operation or during it. When these movable track sections or wheel-engaging bars are used the apparatus becomes complex, and numerous parts are present which are liable to wear and breakage. In operating some coal mines, for instance, it is necessary to effect the tippling and emptying of several thousand 60 cars daily; and the tippling mechanism has to be set in action rapidly, and at quickly recurring intervals. The reciprocating motions of the rising and falling tracks require an appreciable time and the constant wear 65 at journals and bearings rapidly deteriorates at journals and bearings rapidly deteriorates the active parts of the apparatus.

In the present construction I have succeeded in dispensing with all movable track rails or bars for bearing against and moving 70 up and down with the wheels.

In the drawing, C indicates one of the cars, it being shown in the position occupied just before or just after the tippling operation; and C¹, the next succeeding car in the train. 80

The track sections A¹ have the rails a¹—a¹ connected to the rails a—a by the curved or bent parts at a²—a².

Each car is in turn arrested in such way that its front wheels c are stopped at or 85 slightly in advance of the bend at a², this being accomplished by means of laterally movable horns or retaining bars D. Each of these is carried by a lever E, which is pivoted to the framework at e and has an outwardly 90 extending arm e¹.

F is a link or pitman rod extending backward from this lever, to which it is pivotally connected, to a crank arm g on a rock shaft G. The rock shaft extends across the track 95 from one side to the other and is mounted in suitable bearings. Preferably the connecting rods or pitmen F—F are formed of tubes f, which at their ends are secured to rods or castings f¹—f² adapted to be pivoted to the 100 parts E and g.

H are springs, each attached to a rod h secured to a bracket h' and connected at h² to one of the arms e¹.

The springs tend normally to draw the pitmen or connecting rods forward and to swing the hook bars D towards their innermost positions. When the latter are in these posi-

tions they lie in the vertical planes of the treads of the track rails $a-a'$ and therefore in the planes of the peripheries of the car wheels.

5 The front wheels of each car as it reaches its position for unloading impinge upon and are held by these hook rods during the unloading.

Below the track rails and preferably about 10 midway between their vertical planes there is mounted a cylinder I which is provided with connections for steam or compressed air and also with a piston J and a piston rod K. The cylinder oscillates upon the trunnions L, mounted in journal bearings at L supported upon beams of the framework. One of these trunnions or journals is formed 15 with a steam passage from which ducts lead to the end of the interior chamber of the cylinder. With this duct there connects a steam pipe M.

N is a feed pipe connecting with the boiler or other source of supply and O is an exhaust pipe. Between the pipes M, N and O there 20 is interposed a three-way valve P which, when turned to one position, permits the steam to pass to the interior of the cylinder, and, when turned to the other, cuts off the steam and opens the exhaust pipe. To this 25 valve there is connected an operating arm Q which is pivotally connected to a rod R. The latter is joined to the hand lever S pivoted at s.

When the operator thrusts the lever S in 30 one direction it throws the link R, opens the valve at P and permits steam to enter below the piston J. After the lever has made its stroke he throws the lever of the valve in the other direction and the steam is cut off and the 35 cylinder is connected with the exhaust, whereupon the piston returns to its initial position. During each of these movements of the piston the cylinder oscillates first forward and then backward.

40 The piston devices are not connected either to the track rails or any parts thereof or any levers or other devices. On the contrary, it bears directly against the car and is provided with a head W at its upper end which may be 45 either forked to permit it to engage snugly with the axle or it may have an extended cross head adapted to engage with the under side of the car.

Y is a trip device and lever attached to the 50 rock shaft G and projecting up therefrom far enough to be struck by the wheel or lower part of the front end of an advancing car.

U is a stop mounted on the track frame and so arranged as to engage the rear side of the 55 front axle when the car is in position for dumping and prevent its rolling or springing backward. This stop is a bar pivoted at u in a bracket U'. u' is a spring interposed between the bottom of the bracket and the stop 60 bar but tending to hold the latter in its up-

permost position against the stop at u'. The axles of the cars impinge upon this swinging stop bar at u' and as they are going forward press it down to such an extent that they are permitted to pass it. As soon as they pass it 70 the bar moves back again under the action of the spring u' when the horns D are in position holding a car. This stop U is, as aforesaid, immediately behind the axle and prevents its moving backward.

The operation of the devices that have been described will be readily understood. If a loaded car be assumed to be standing in a position indicated in full lines Fig. 1, the operator first moves the lever S to the proper 75 position to let the steam enter the cylinder I below the piston J. The latter rises and engages directly with the axle or the under side of the car bottom and the continuing action of the steam results in the lifting of the rear end of the car around the front axle as a hinge. The front door being opened, the contents of the car slide out therefrom. The operator then moves the lever S in the opposite direction, the steam is cut off and the exhaust is open. When the rear wheels of the 80 car have been returned to the track rails at a, the next incoming car is started forward. It presses against the trip lever Y and rocks the shaft G which in turn through the links or pitmen F swings the horns or holding bars D outward away from the planes of the car 85 wheels, and the car which has just been unloaded starts forward on the sharply descending track sections at A'. As soon as its rear 90 wheels have passed the horns at D the latter are returned to their inner position by the springs H and the next car is stopped by them ready to have its contents discharged 95 by a repetition of the steps of operation just 100 described.

I have devised and made mechanism for 105 controlling the action of the piston so that it shall move slowly when it commences its forward stroke and also when it is finishing its 110 backward stroke. The steam duct through the trunnion is extended as shown at I' along the side of the cylinder to the bottom thereof and communicates with the interior ports i and i'. That at i' is directly at the bottom 115 while that at i is at a distance somewhat farther up. The steam is always free to pass through the port at i' even when the piston is at its lowermost point. But it cannot pass through the port i when the piston is down, 120 the latter being of such length as to extend to a plane somewhat beyond it.

The port i' is of a very small area while that at i is considerably larger. Consequently when the steam is first turned on a 125 relatively slow movement will be imparted to the piston and this will continue until the head at W engages with the axle or with the bottom of the car, and just as such engagement commences the larger port at i is 130

opened and the full pressure of the steam is admitted after which the lifting of the car will be rapidly effected.

When the car is descending, and also the piston, it will come down comparatively rapidly until it has passed the port *i*, and then will be cushioned by the steam at the lower end of the cylinder whose rapid escape therefrom is impeded because of the small area of the port at *i'*.

What I claim is:

1. In a car unloading apparatus, the combination of a track, means for holding a car against forward movement thereon, and a stop for holding the car against backward movement comprising a bracket *U'*, a stop bar pivoted to said bracket and arranged to engage with an axle of the car, and a spring for holding the stop bar in position, and at the same time allowing it to yield to the forward movement of a car, substantially as set forth.

2. In a car unloading apparatus, the combination of the track, the cylinder and the piston arranged to transmit power to the car to elevate it, means arranged at the front end of the car for preventing it from moving forward and means also arranged at the front end of the car for holding it against movement backward while it is being elevated, substantially as described.

3. In a car unloading apparatus, the combination of the track, the cylinder and piston adapted to transmit power for elevating the car, means for holding the car against forward movement and the automatically acting yielding stop for holding the car against backward movement while it is being elevated, substantially as described.

4. In a car unloading apparatus, the combination of the car track, the piston for transmitting power to the car to elevate it, the cylinder containing the piston, means for de-

livering steam at a relatively reduced pressure to the cylinder and against the piston when it is near the lower end of its path and for delivering steam at a relatively greater pressure after it has engaged with the car, substantially as set forth.

5. In a car unloading apparatus, the combination of the track, the piston adapted to engage with a car thereon, and transmit power thereto to elevate it, the cylinder containing the piston, a duct having a relatively reduced communication with the piston chamber when the piston is near the end of its path and relatively increased communication therewith after the piston has traveled over part of its path, substantially as set forth.

6. In a car unloading apparatus, the combination of the car track, the piston adapted to engage with a car and transmit power thereto to elevate it, the cylinder containing the piston having a relatively reduced port near the end of the piston, and a relatively enlarged port at a point more remote from the said end, and a steam duct communicating with both the said ports, substantially as set forth.

7. In a car unloading apparatus, the combination of a car track, a piston transmitting power to the car for elevating it, a cylinder containing the piston, and means for introducing motor fluid into and exhausting it from the cylinder comprising a duct having two ports leading into the cylinder at different distances from one end thereof and adapted to control the movements of the piston from that end of the cylinder.

In testimony whereof I affix my signature in presence of two witnesses.
